UNITED STATES PATENT OFFICE.

WILLIAM VOGEL, OF CHICAGO, ILLINOIS, ASSIGNOR TO G. A. WOOLLEY, OF SAME PLACE.

APPARATUS FOR AND PROCESS OF CONSUMING SMOKE.

SPECIFICATION forming part of Letters Patent No. 295,842, dated March 25, 1884.

Application filed December 28, 1883. (No model.)

To all whom it may concern:

Be it known that I, WM. VOGEL, of Chicago, in the county of Cook and State of Illinois, have invented certain new and useful Improvements in Apparatus for and Process of Consuming Smoke; and I do hereby declare the following to be a full, clear, and exact description of the invention, such as will enable others skilled in the art to which it pertains to make and use it, reference being had to the accompanying drawings, which form part of this specification.

My invention relates to an improvement in an apparatus for and process of consuming smoke, and is designed to be attached to and operated in connection with steam-boilers and other furnaces of the ordinary construction.

The object of my invention is, first, to consume the smoke from the furnace; second, to separate the soot and other products of combustion from the smoke and deposit the same in the form of lamp-black of commercial value in the bottom of the cylinders; third, to conduct the gas resulting from the decomposition 25 of the smoke into the furnace and to use it as an auxiliary to the fuel therein.

The accompanying drawings represent an apparatus embodying my invention.

Figure 1 is a side elevation. Fig. 2 is a vertical section, showing the apparatus attached to a furnace. Fig. 3 is a horizontal section on the line $x x$, Fig. 2. Fig. 4 is a top plan view.

A represents a cylinder that is made of boiler-plate or other suitable material, and has located in it and secured in place a number of small cylinders, B, grouped around a central cylinder, H, as shown. These cylinders are connected together at their upper and lower ends, as at A'. An inlet-pipe, I, is connected 35 to one of the cylinders B at the lower end thereof, and an outlet-pipe, K, is connected to the upper end of the cylinder H. A water-pipe, L, passes under the cylinder A, and is connected to the small cylinders, as at M. Cocks N 45 allow the water to be introduced into or drawn from the group of cylinders. Extending vertically through the small cylinders, and journaled centrally therein, are the shafts O, which have a number of radial beaters, P, projecting 50 from them. From the inner side of the cylin-

ders project the arms Q, which are so arranged as to be out of line with the beaters P. Upon the central shaft, O', is affixed a spur-wheel, R, and to the shaft O are secured the pinions S, which mesh with the wheel R. By means 55 of a pulley, T, the shaft O' is rotated, and its motion, by means of the gear-wheels R S, is imparted to the shaft O in the cylinders. Connected to the inlet-pipe I is a blower, V, and communicating therewith is a cooling-cylinder, W, of any suitable construction. In Fig. 2 I illustrate a furnace, C, of which D represents the fire-chamber, E the grate, and F the ash-pit. A pipe, G, leads from the flues of the furnace to the cooler W, and the outlet-pipe 60 K terminates at a suitable point below the grate E.

X represents water-indicators.

The operation of my invention is as follows: The small cylinders are filled with water up to 70 a suitable point, as shown. The smoke passes from the furnace through the pipe G into the cooling-cylinder W. From thence it is acted upon by the blower V and forced through the pipe I into the bottom of one of the cylinders 75 B, up through the water therein into the air-space Y, from thence through the opening A' into the adjoining cylinder, down through the water in said cylinder and through the connection A' into the next adjoining one, and 80 so on through the entire group. The smoke during its passage through the water in the cylinder is constantly operated upon by the beaters P and arms Q, and by the time it reaches the cylinder H is entirely decomposed. The 85 soot gravitates to the bottom of the several cylinders and is there deposited in the form of lamp-black, of commercial value. During the passage of the smoke through the water in the cylinders a gas results therefrom, which is fed 90 through the pipe K to the pit in the furnace, as previously stated. By means of my invention I consume the smoke, collect the valuable lamp-black, which would be otherwise wasted, and produce a gas which is valuable as an auxiliary to the fuel in the furnace.

Having thus described my invention, I claim—

1. The process of consuming smoke, which consists of forcing it through a series of vessels 100

filled with water and subjecting it to the action of the beaters or agitators therein, substantially as set forth.

2. The combination of the cylinders B, wa-
5 ter-supply pipe L, beaters P, and an inlet-pipe, substantially as described.

3. The combination of the cylinders B H,
water-supply pipe L, inlet-pipe I, blower V,
and an outlet-pipe, K, with beating devices
10 are adapted to operate within the cylinders,
substantially as shown and described.

4. The combination of the cylinders B H,
water-supply pipe L, inlet-pipe I, blower V,
cooler W, and an outlet-pipe, K, with beating
or agitating devices that are adapted to operate 15
within the cylinders, substantially as specified.

In testimony whereof I affix my signature in
presence of two witnesses.

WILLIAM VOGEL.
